UNITED STATES PATENT OFFICE.

ARCHIE D. FOREY, OF CLARKSVILLE, IOWA.

ADJUSTABLE GAME DEVICE.

Application filed July 25, 1927. Serial No. 208,334.

My invention relates to improvements in adjustable game devices, and the object of my improvements is to provide a game device constructed and arranged for such adjustments as will render its action fortuitous in a manner to largely obviate such advantages as would ordinarily be possessed by a practiced player accustomed to a device of this class deprived of such adjustments.

This object I have accomplished by the means which are hereinafter described and claimed, and which are illustrated in the accompanying drawings, in which Fig. 1 is a side elevation, and Fig. 2 is a plan of my improved game device. Fig. 3 is an enlarged front elevation of the propelling device thereof. Fig. 4 is a detail perspective view on a still larger scale of the special spring device employed with said propelling means.

The game device illustrated is specifically that to be used for a basket ball game, but it is to be understood that the invention herein is not limited to this species of game, but that such modifications may be effected therein as will adapt the device for other games to which its principles of operation may be applicable without departing from the invention or the scope of the claims.

The numeral 1 denotes a base plank having longitudinally spaced cross bars 2 fixed upon its under face, divergent pairs of legs 3 being fixed upon said cross bars to suitably position the plank 1 from a supporting surface. Upon the rear part of the plank 1 are secured a pair of transversely spaced sockets 4 in which are fixed the lower ends of a pair of vertical tubular standards 5 of the same length. Rods 6 are slidably seated in the bores of said standards 5, and may be secured therein by means of set-screws 7. A cross bar 8 is fixed upon the upper ends of said rods horizontally and a rectangular back-board 9 is fixed upon said cross bar to project upwardly vertically therefrom. A transversely apertured bracket fixture 10 is mounted upon the front face of the back-board 9 medially and below its center, and fixedly carries a horizontal ring 11, projecting forwardly. It will be seen that the back-board 9 and the ring 11 may be adjusted vertically by the means described.

The numeral 12 denotes a propeller arm, made of wood or other suitable substance and having its rear part diminished and furnished with a fixed metal projection 18

having a hole 19. A short standard 20 has its lower threaded end fixed in the medial line of the base plank 1, secured by a nut 22 on its threaded end, and has a forwardly hooked terminal 21 which is inserted loosely in the hole 19 of said arm projection 18, the hole being large enough to permit considerable play to said projection and arm.

A spring device is engaged between the lower rear part of the arm 12 and the top of the plank 1. This device consists of a single spring rod bent and shaped as follows. The rod is bent to provide a transverse medial reach 24 having arm parts directed to one side, the rod being provided with several coils 26 at the end of each arm part, and from said coils straight arm parts 23 project in a direction opposite to that of the arm parts first mentioned and have downwardly bent terminations 25 which are seated in holes provided in the top of the plank 1 to anchor the device thereto, with the reach 24 in contact transversely with the under face of the arm 12 about midway of its length.

The numeral 14 denotes a rod bent in an inverted U-shape having a medial transverse reach part 13, the side members being terminally threaded and passed downwardly through holes in the plank 1, where they are secured for vertical adjustments relative thereto by nuts 15 and 16. The reach 13 crosses the arm 12 a distance from its forward end, and the arm 12 has in advance of said reach 13 a circular hollow seat 17 to receive a basket ball 27.

A player may manually depress the forward end of the arm 12 while compressing the spring device thereunder, and then release the arm, the reacting spring swinging up the arm and projecting the ball 27 toward the ring 11. If the ball falls through the ring a count is recorded for the player. When the arm 12 strikes the reach 13 in swinging upwardly, it is stopped, but the ball is projected upwardly as stated, to ordinarily strike the back board 9 and bound to fall either within or outside of the ring 11. The back board 9 may be first adjusted in position vertically by the means described, to vary the distance of the ring 11 from the propeller arm 12. This means of adjustment of the relative position of the ring 11 in a measure prevents a practiced player from acquiring a skill at playing which will give an advantage over players

not having the same experience, and therefore it is fair that before beginning a game, the position of the ring should be changed enough to obviate the advantages of practice when the ring is in one position.

However, a player may nevertheless by practice gage the different adjustments possible for said ring 11, so I have supplied other means of adjustment operative upon 10 the propeller arm 12, which may be initially adjusted so as to render it very unlikely that any player can acquire such skill by practice as to much surpass an inexperienced player. This adjustment is secured as follows.

The nuts 15 and 16 on either side member of the looped device 14 are manipulated to, push up either member to a greater height than the other member, thus, as 20 shown exaggerated in Fig. 3, including the reach part 13 laterally, the rod yielding at both angles of bending. As the arm 12 has its rear fixed projection 18 loosely mounted upon the depending end part 21 of the short 25 fixed standard 20, the arm 12 is free to turn sidewise enough when it strikes the inclined reach 13 in moving upwardly to conform to the inclination thereof, so that at the moment of stopping the arm and projecting 30 the ball 27, a sidewise impulse is given to the ball 27, so that it is not impelled upwardly and rearwardly over the center of the ring 11, but a little to one side of the center thereof. The ball may lightly strike 35 the ring on this account in dropping, lessening the chances of its dropping through it, according to the manner of dropping the ball, so that the ball in striking the ring may fall inwardly through the ring, or if a 40 little too far displaced from the center of the ring, will bound off the ring outwardly. The two means of adjustment, therefore, can be used to equalize the chances between different players, fortuitously. Aside from

these uses, however, if it is desired to maintain the back board and the reach 13 in horizontal positions, this may be accomplished by using both means of adjustment for 45 truing their relative positions.

Having described my invention, what I 50 claim as new, and desire to secure by Letters Patent, is:

1. A device of the character described, comprising a game ball, a horizontal ring mounted at a desired altitude, a resiliently 55 controlled propelling device for said ball mounted loosely to be freely tilttable in any direction, means for limiting the scope of movement of said device, and means for varying the said limiting device in position 60 to variably tilt the propelling device when striking the limiting device.

2. A device of the character described, comprising a game ball, a horizontal ring mounted and supported for vertical adjustments, a resiliently controlled propelling arm mounted loosely for projecting said ball toward said ring, and a stop member crossing said arm and adjustable for lateral inclinations relative thereto to limit the scope 70 of movement of the arm while propelling said ball and to impart to the ball when striking the inclined stop member a sidewise deflection in its course.

3. A device of the character described, 75 comprising a game ball, a horizontal ring mounted fixedly at a desired altitude, a resiliently controlled propelling arm mounted loosely for projecting said ball toward said ring, and a stop member crossing said 80 arm and adjustable for lateral inclinations relative thereto to limit the scope of movement of the arm while propelling said ball and to impart to the ball when striking the inclined stop member a sidewise deflection 85 in its course.

In testimony whereof I affix my signature.
ARCHIE D. FORRY.
